FIG.20

FIG. 1 is a front elevational view of a portable sewing machine showing my new design in a closed position;

FIG. 2 is a rear elevational view thereof;

FIG. 3 is a side elevational view;

FIG. 4 is a side elevational view of the side opposite that shown in FIG. 3;

FIG. 5 is a top plan view;

FIG. 6 is a bottom plan view;

FIG. 7 is a top plan view on a reduced scale of the portable sewing machine in an opened position of use;

FIG. 8 is a bottom plan view thereof;

FIG. 9 is a rear perspective view;

FIG. 10 is a side perspective view of the portable sewing machine in a closed position of storage;

FIG. 11 is a front perspective view of the portable sewing machine in an open position of use;

FIG. 12 is a front perspective view of the portable sewing machine in a closed position;

FIG. 13 is a side elevational view of the portable sewing machine in an open position of use;

FIG. 14 is a side elevational view of the side opposite that shown in FIG. 13;

FIG. 15 is a front elevational view thereof;

FIG. 16 is a rear elevational view;

FIG. 17 is a side perspective view;

FIG. 18 is a side perspective view of the portable sewing machine in a closed position;

FIG. 19 is a rear perspective view of the portable sewing machine in a position of use; and

FIG. 20 is a rear perspective view of the portable sewing machine in a closed position of storage.

I claim:

The ornamental design for a portable sewing machine, substantially as shown.
